(57) **CLAIM**

The ornamental design for a medical retractor, as shown and described.

DESCRIPTION

FIG. 1 is a front view of a medical retractor;

FIG. 2 is a bottom view of the medical retractor of FIG. 1; FIG. 3 is a top view of the medical retractor of FIG. 1; FIG. 4 is a right side view of the medical retractor of FIG. 1;

FIG. 5 is a left side view of the medical retractor of FIG. 1; FIG. 6 is a perspective view of the medical retractor of FIG. 1;

FIG. 7 is a front view of a second embodiment of a medical retractor;

FIG. 8 is a bottom view of the medical retractor of FIG. 7; FIG. 9 is a top view of the medical retractor of FIG. 7; FIG. 10 is a right side view of the medical retractor of FIG. 7;

FIG. 11 is a left side view of the medical retractor of FIG. 7;

FIG. 12 is a perspective view of the medical retractor of FIG. 7;

FIG. 13 is a front view of a third embodiment of a medical retractor;

FIG. 14 is a bottom view of the medical retractor of FIG. 13; FIG. 15 is a top view of the medical retractor of FIG. 13; FIG. 16 is a right side view of the medical retractor of FIG. 13;

FIG. 17 is a left side view of the medical retractor of FIG. 13;

FIG. 18 is a perspective view of the medical retractor of FIG. 13;

FIG. 19 is a front view of a fourth embodiment of a medical retractor;

FIG. 20 is a bottom view of the medical retractor of FIG. 19; FIG. 21 is a top view of the medical retractor of FIG. 19; FIG. 22 is a right side view of the medical retractor of FIG. 19;

(Continued)

FIG. 23 is a left side view of the medical retractor of FIG. 19;

FIG. 24 is a perspective view of the medical retractor of FIG. 19;

FIG. 25 is a front view of a fifth embodiment of a medical retractor;

FIG. 26 is a bottom view of the medical retractor of FIG. 25;

FIG. 27 is a top view of the medical retractor of FIG. 25;

FIG. 28 is a right side view of the medical retractor of FIG. 25;

FIG. 29 is a left side view of the medical retractor of FIG. 25; and,

FIG. 30 is a perspective view of the medical retractor of FIG. 25.
